US0D1022609S

(12) **United States Design Patent** (10) **Patent No.:** **US D1,022,609 S**
(45) **Date of Patent:** **** Apr. 16, 2024**

(54) **PIZZA BOX**

(71) Applicant: **Chupeng Zhan**, Huizhou (CN)

(72) Inventor: **Chupeng Zhan**, Huizhou (CN)

(**) Term: **15 Years**

(21) Appl. No.: **29/907,975**

(22) Filed: **Jan. 10, 2024**

(30) **Foreign Application Priority Data**

Jul. 17, 2023 (CN) 202330445583.9

(51) **LOC (14) Cl.** **07-09**

(57) **CLAIM**

The ornamental design for a pizza box, as shown and described.

DESCRIPTION

FIG. 1 is a perspective view of a pizza box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view thereof.

The broken lines in the drawings depict portions of the pizza box that form no part of the claimed design.

1 Claim, 9 Drawing Sheets
